UNITED STATES PATENT OFFICE.

FRANK B. BIGELOW, OF DETROIT, MICHIGAN.

ARCH CONSTRUCTION FOR FURNACES.

Application filed January 15, 1923. Serial No. 612,630.

To all whom it may concern:

Be it known that I, FRANK B. BIGELOW, a citizen of the United States, residing at Detroit, in the county of Wayne and State of Michigan, have invented certain new and useful Improvements in Arch Constructions for Furnaces, of which the following is a specification.

In furnaces having renewable brick arches 10 in which the injured or damaged bricks may be individually removed and replaced with new ones, in one style of structure, each brick is supported from above by its own hanger, the brick being grooved for the 15 reception of a supporting shoe hung on the lower end of the hanger.

Such brick groove is desirably undercut in cross-section for the retention of the shoe therein and it is open at both ends, whereby 20 the shoe may be inserted in and withdrawn from the groove at either end of the latter.

In other words, the shoe is slidably mounted in the brick groove and hence the brick is likely to fall off of the shoe when 25 it is being inserted in the arch if the shoe becomes accidentally tilted or inclined.

The present invention provides simple and inexpensive means for locking the shoe to the brick to avoid the possibility of such 30 unintentional separation, yet it permits the ready placement of the shoe in the groove and its removal therefrom if at any time that becomes desirable.

In order to enable those skilled in this art 35 to fully understand the structural and functional advantages of a furnace embodying this invention, in the accompanying drawings forming a part of this specification, I have illustrated desirable and preferred embodiments of the invention and in the several views of the drawings, like reference characters have been used to designate the same parts.

In these drawings:

40 Figure 1 is a fragmentary sectional view taken from the rear of the furnace looking forwardly into the latter, some of the elements of the structure being omitted to more clearly depict the details of construction;

Figure 2 is a longitudinal vertical section through the upper portion of the furnace showing a modified form of arch brick hanger;

45 Figure 3 is a fragmentary longitudinal vertical section on an enlarged scale through

the back part of the arch showing the supporting means for the bricks, the hangers for the main bricks of the arch being like those shown in Figure 1;

60 Figure 4 is a vertical fragmentary cross-section through a portion of the arch, shown in Figures 1 and 3, near one side of the arch; and

Figure 5 is a perspective view of one of 65 the arch bricks and the style of hanger shown in Figure 2.

In the particular embodiments shown, although as will be obvious to those skilled in this art, the invention may be satisfactorily 70 employed in furnaces of radically different styles, the furnace is of the usual "Murphy" type comprising a V-shaped grate 11, a clinker grinder 12, opposed coking-plates 13, 13 associated sidewise-reciprocating stoker-boxes 14, 14, superposed fuel-magazines 15, 15, air flues 16, longitudinal arch-plates 17, 17, and rows of arch-plate bricks 18, 18, supported on the arch-plates and held or locked in position by appropriate latches 19, the 80 lifting or elevation of which releases the bricks permitting their ready replacement.

The flat suspended arch proper 20 is composed of a plurality of bricks 21 arranged in horizontal, longitudinal and transverse 85 rows, as is clearly depicted in Figure 1, and, when the arch is new, all of these bricks or refractory blocks will be of practically the same thickness and will unitedly present a substantially-smooth lower face. 90

Each such arch-brick has an undercut or inverted T-shaped groove 40 in its top face for the purpose of accommodating or receiving a suitably-shaped, transversely-aper-tured shoe 22 having an enlarged lower part 95 occupying the undercut section of the brick cavity.

Each brick shoe of this kind, except those at the side and rear margins of the flat arch, in the embodiment of the invention shown 100 in Figures 1, 3 and 4, is supported from a pipe 23 above by means of a chain 24 with hook ends 25 and 26, the former taking into the eye or hole of the shoe and the latter engaging the appropriate link of the chain to support the brick at the desired or required height, such elevation of the brick obviously 105 being subject to adjustment by catching the hook in any desired link of the chain.

The construction comprises one such upper, apertured pipe for each longitudinal row of bricks, these several pipes being suffi-

ciently high above the bricks to permit the replacement of any one of the latter without disturbance of the others, the pipes being supported by front and rear cross I-beams 27 of which only the latter is shown in Figures 1 and 3.

At the front of the furnace such pipes are open to the outer air through the furnace front-plate as shown in Figure 2 which illustrates another embodiment of the invention, such connection to the outer air being common to all embodiments of the invention.

Each such pipe extends rearwardly through registering holes in the webs of the corresponding I-beams projecting back of the rearmost one some distance as shown in Figures 2 and 3.

In the operation of the furnace, outer air, by the draft of the appliance, is drawn in through these several pipes and delivered through their holes or apertures near their rear ends in small jets into the space above the arch, thus keeping the pipes cool and supplying a portion of the air for carrying on the combustion.

Spaced, longitudinal inverted T-bars 28 are mounted on the tops of the transverse I-beams and between and supported on these are removable cover tiles 29 which give ready access to the hangers for the bricks of which the arch is composed.

The side marginal or border bricks 31 of the flat arch located partly above the arch-plate bricks 18 are hung from above on the outermost pipes 23 by means of hangers which give great refinement of regulation as to length.

Each such brick has one of the usual shoes 22, but this is suspended from the pipe by a reversely-threaded turn-buckle hanger 32 which gives opportunity for nicety of adjustment as to length thus accurately governing or gauging the position of the brick which it supports.

The flat under surface of each brick 31 must bear on the top plane face of the corresponding lower arch-plate brick with sufficient pressure to assure a comparatively or relatively tight joint between them, but this pressure must not be sufficient or great enough to materially hamper or retard the bodily movement of the upper brick over the lower one as is caused by the expansion and contraction of the arch under the wide ranges of temperatures to which it is subjected.

At the rear of the furnace, the projecting part of each pipe 23 supports an apertured seal-brick 33 mounted directly on the end of the pipe by the reception of the latter in its cavity, the brick or block being held in place on the pipe by a pipe-plug 34 maintained in position by a catch 35 inside of the pipe and having a downturned end engaging a hole in the pipe, all as is fully shown in Figure 3.

The part of the brick recess accommodating the plug but not occupied by the latter is filled by a fire-clay plug 36, all as will be readily understood and as is fully illustrated in Figure 3.

The end-bricks 37 of the arch are of the cross-sectional shape indicated in Figure 3, and they are individually or separately supported on the several pipes by turn-buckle or other suitable hangers 38 in much the same manner that the bricks 31 are held in position.

The accurate and delicate screw-thread adjustment permitted by such hangers allows the co-acting flat faces of the bricks 37 and 33 to be brought into and kept in proper contact under all conditions of service, thus rendering certain and guaranteeing the correct tightness or seal of the joint without interference with the necessary relative movements of these parts by reason of expansion and contraction of the elements of the structure subjected to the heat of the furnace.

In Figure 1 of the drawing all of the bricks of the main body of the arch are of the same thickness and their hangers are adjusted for uniform length. This condition could well represent the construction when it is first installed.

It is to be understood however that the arch need not be flat since it may have an upward curvature more or less as may be required or desired.

In Figures 3 and 4 the bricks or refractory blocks are of different thicknesses and their hangers or supporters have been adjusted accordingly to cause them to present a practically smooth under surface exposed to the direct heat of the furnace.

An arch of this general character usually requires repairing rather than the renewal of the entire arch, and if a local deterioration can be repaired easily and inexpensively, as is permitted by this improved construction, the life of the arch as a whole is lengthened many times.

In this new structure, the space at the rear of the arch is closed by special bricks or blocks, so attached or supported that they cannot be forced off of the supporting members by the expansion of the arch and at the same time the construction keeps the joints tight thus avoiding an inefficient operation of the furnace or an injurious flow or passage of the heated gaseous products of combustion.

It should be noted in passing that the arch-plate bricks are independently supported or held in place and can be quickly and easily removed and replaced without interfering with any other portion of the arch.

Thus every brick in the arch is independently supported and can be taken out and replaced without disturbing the balance

of the arch or in some cases it may be preferable to carry more than one brick on each hanger.

The present improved construction, as will be understood without difficulty, provides for the elimination of expansion strains, and the cracking and spalling of bricks due to the expansion and pressure of adjoining bricks.

10 In the form of the invention, illustrated in Figures 2 and 5, the hangers 41 for the main bricks of the arch comprise metal rods bent into hook-shape at their opposite ends at 42 and 43 to afford means to engage 15 the eyes or holes of the shoes of the bricks and to hang over the supporting pipes.

To modify the lengths of such hangers, their end portions are merely bent more or less to increase or shorten their lengths for 20 the purposes above indicated.

Now as to all of the bricks 21, 31 and 37, their inverted T-shaped grooves 40 extending the full lengths of the bricks are intersected at the middle of each brick by a 25 transverse shallower groove 44 in register with the hole or eye of the brick shoe and adapted to accommodate the lower hook of the hanger, whatever its form may be, which hooks into the aperture of the shoe.

30 Thus, whereas the shoe 22 may be readily slid into its brick groove 40, the shoe is locked to the brick just as soon as the lower hook of the hanger is hooked into the shoe, and since such hook is accommodated in 35 the cross-groove or channel, it demountably locks the brick and shoe together so that there is no danger of the former sliding off of the latter when they are being inserted in place in the furnace.

40 Of course they are readily unlocked just as soon as the hanger and shoe are separated.

Such positive and assured attachment of the bricks to their shoes and hangers greatly facilitates the handling of the bricks by means of their supporting hangers during their introduction into the furnace and their insertion in proper place in the brick arch.

The invention is not limited and restricted 50 to the precise and exact details of structure shown and described since these may be modified within radical limits without departure from the heart and essence of the invention and without the sacrifice of any of its substantial benefits and advantages.

I claim:

1. In an arch construction of the character described, the combination of a brick having a groove in its top face open at least at one 60 end, a supporting shoe in said groove, means to lock said shoe against substantial movement longitudinally in said groove, and means to support said shoe from above.

2. In an arch construction of the character 65 described, the combination of a brick having

a groove in its top face open at least at one end, a supporting shoe in said groove, and means to support said shoe from above, said latter means locking said shoe against movement in said groove.

3. In an arch construction of the character described, the combination of a brick having an undercut groove in its top face open at both ends, a supporting shoe in said groove, means to lock said shoe against movement in said groove, and means to support said shoe from above.

4. In an arch construction of the character described, the combination of a brick having in its top face a main groove and a supplemental groove intersecting said main groove, a shoe in said main groove, means in said supplemental groove cooperating with said shoe to lock the latter against movement in said main groove, and means to support said shoe and its brick.

5. In an arch construction of the character described, the combination of a brick having a main undercut groove and a supplemental groove intersecting said main groove, an apertured shoe in said main groove with its aperture in register with said supplemental groove, means in said latter groove cooperating with the aperture of said shoe to lock the shoe against movement in said main groove, and means to support said shoe and its brick.

6. In an arch construction of the character described, the combination of a brick having a main undercut groove open at both ends and a supplemental groove intersecting said main groove, an apertured shoe in said main groove with its aperture in register with said supplemental groove and a hanger for said shoe having a hook in said supplemental groove and extended through the aperture of said shoe thereby locking the latter against movement in said main groove.

7. An arch brick for furnaces having a groove in its top face open at least at one end and designed to accommodate a supporting shoe for the brick and another groove in the same face of the brick at an angle to and intersecting said first groove and provided to receive a lock for said shoe to hold the latter against substantial movement longitudinally in the first groove.

8. An arch brick for furnaces having an undercut groove extended the full length of the top face of the brick and open at both ends and designed to accommodate a supporting shoe for the brick and a cross-groove in the same face of the brick intersecting at least a portion of said first groove and provided to receive a lock for said shoe to hold the latter against substantial movement longitudinally in the first groove.

In witness whereof I have hereunto set my hand and seal.

FRANK B. BIGELOW. [L. S.]
